UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,139, dated September 29, 1896.

Application filed August 24, 1896. Serial No. 603,798. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of an arrangement of fleur-de-lis-shaped figures or ornaments arranged at regular distances apart over the surface of paper, as represented in the accompanying drawing.

15 The border for the said design is formed of similar fleur-de-lis-shaped figures or ornaments, which alternate with large ornamental figures connecting said fleur-de-lis-shaped figures by ornamental scrolls, as shown, and a wide ornamental band below said figures, as 20 shown in the drawing.

What I claim is--

1. The design for wall-paper herein shown and described.
2. In the design for wall-paper the border 25 herein shown and described.

Witness my hand this 10th day of August, 1896.

CHARLES BOOZ.
